(57) CLAIM

The ornamental design for a holder for hair styling tools, as shown and described.

DESCRIPTION

FIG. 1 is a perspective view of a holder for hair styling tools in accordance with my design;

FIG. 2 is a front elevational view of the holder for hair styling tools of FIG. 1;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken lines shown in the drawings illustrate the environment of the holder and form no part of the claimed design.
